FIG 3

Walter V. Hart,
Inventor,
by Alvin J. Schmidt,
his Attorney.

UNITED STATES PATENT OFFICE.

WALTER V. HART, OF JACKSONVILLE, FLORIDA; ELSIE HART HEDDON ADMINISTRATRIX OF SAID WALTER V. HART, DECEASED.

BOX-MAKING MACHINE.

Application filed April 28, 1924. Serial No. 709,492.

To all whom it may concern:

Be it known that I, WALTER V. HART, citizen of United States, residing at Jacksonville, county of Duval, and State of Florida, have invented certain new and useful Improvements in Box-Making Machines, of which the following is a specification.

My invention relates to box making machines of the class in which certain members of the box are held stationary in fixed positions while other members of the box are being nailed in place to form the complete box.

The main and particular object and advantage of this invention is to provide a machine on which boxes may be nailed accurately together in the shortest possible time, with the least amount of manual labor and without necessitating a highly skilled operator. A further object is to provide such a machine of rugged construction, few parts, and comparatively inexpensive to manufacture.

These and various other objects and advantages will be readily understood from the following specification and from the accompanying drawings of a preferred embodiment of my invention, but it will be understood that various modifications might be made without departing from the scope of the invention.

Fig. 1 is a front elevation of the preferred embodiment of my invention.

Fig. 2 is a plan view, and

Fig. 3 is a side elevation of same.

In a general way the machine may be said to consist of a fixture in which certain members of a box are held. This fixture is mounted on a stand in such a manner that it may be rotated by means of a treadle, so that the side on which the operator works is always uppermost. After the assembling of the box is completed, the fixture is returned to its original or starting position by means of the treadle.

Referring now to all views, simultaneously, 1 is the top of a stand which is provided with four legs 2. Each pair of these legs is provided with a brace 3. The top 1 is solid and forms a bench upon which the work of the machine is performed. Extending upwardly from each end of the top 1 are brackets 4. These brackets are provided with guide strips 5 and 6.

The fixture for holding the box ends and partitions in place while the sides and bottom are being nailed on, consists of a base plate 7 from which extend two end pieces 8 and 9 and a center piece 10. In close proximity to the end pieces and the center piece, 55 springs 11, 12, and 13 are placed. These springs are attached to the base plate 7. The end pieces 8 and 9, the center piece 10, as well as the springs 11, 12, and 13 are rectangular in shape and have the conformity 60 and size of the inside of the box to be assembled. The end pieces of the fixture are provided at their centers with outwardly extending studs 14, on which the fixture may 65 be revolved. In its normal position, the fixture rests directly on the solid top 1. Bushings 15, free to slide up and down between the guide strips 5 and 6, are inserted between these guide strips and in these bushings the 70 studs 14 revolve.

Cams 16 are rigidly attached to the studs 75 14. These cams are provided with four notches 17, 18, 19, and 20. Notches 17 and 18 are used in turning the assembling fixture while nailing the box together, while 80 notches 19 and 20 are used for returning the fixture to its original position. These operations will presently be explained. Operating levers 21 are connected by means 85 of levers 22 to a treadle 23, in the well known manner illustrated. The upper parts 90 of the operating levers 21 are forked, as shown at 24, and in these forked parts studs 25 are riveted. These studs engage with the notches in the cams 16, when the treadle 23 is depressed.

It will be noted that the operating levers 95 21 are not placed on a line drawn through the center of the machine. This is indicated by 26 and 27 which represent the center lines of the operating levers and the machine respectively. It is plain that when the treadle 23 is depressed, the studs 25 will engage in the notches 17 and lift the assembling fixture, at the same time revolving it 100 one-quarter turn. If the treadle is again depressed, the studs will engage in notches 18, lift and revolve the fixture an additional quarter turn.

When it is desired to return the fixture to its original position, the studs 25 in the operating levers 21 must engage in notches 19, which by this time have been turned over

to their operating position. To do this it is necessary to move the operating levers to the other side of the center line 27; this is accomplished in the following manner:

- 5 Referring particularly to Fig. 2, it will be seen that the operating levers 21 slide in square bushings 28 and that these bushings are slideably mounted in frames 29 located at both ends of the stand. These frames are 10 also slideably mounted, the bolts 30 passing through the slots 31 and are screwed into the stand. The bushings 28 are held in a central position in the frames 29 by the tension springs 32 and 33, one end of each of 15 which is fastened to the bushings 28, while the other ends are hooked over pins 34 and 35, which are riveted in the frames as shown. These springs have purposely been omitted on Figs. 1 and 3 to simplify these views.
- 20 The frames 29 are provided at each end with members 36 and 37, bent at right angles to the frames and extending inwardly toward the center of the machine. Rocker arms 38 are pivoted at their centers on 25 cross members 39, forming part of the brackets 4. The ends of these rocker arms are made with inclined cam faces 40 and 41. The end pieces 8 and 9 of the assembling fixture are provided with pins 42 and 43 30 which engage with the rocker arms 38 when the fixture is revolved. It will be readily seen that the engagement of either the pins 42 or 43 with the rocker arms 38 will cause the frames 29 to slide to one side 35 or the other through the action of the cam faces 40 or 41 on the members 36 or 37. Flat springs 44 and 45, riveted on the brackets 4, hold the rocker arms in place by the friction exerted by them on the rocker arms.
- 40 To partly counterbalance the weight of 45 the assembling fixture and the box placed therein, two tension springs 46 and 47 are attached under the top of the stand while their other ends are attached to a flat metal bar 48, as plainly shown on Figs. 1 and 3. These springs act upon the fixture by 50 means of rods 49, secured in sockets 50, formed on the bushings 15. The lower ends of the rods 49 are threaded and supplied with nuts 51, by means of which the tension on the springs 46 and 47 may be regulated.

The machine is used in the following manner:

- 55 The box ends are inserted between the end pieces 8 and 9 and the springs 11 and 13; and the box partition between the center piece 10 and the spring 12 of the assembling fixture. The boards forming the side of the box are now nailed in place on top of the fixture. A depression of the treadle causes 60 the fixture to revolve one-quarter turn. The boards forming the bottom of the box are now nailed on the side uppermost. The next depression of the treadle revolves 65 the fixture another quarter-turn, but as the

fixture revolves, the pin 43 depresses the rocker arm 38, causing the inclined cam face 42 to move the frame 29, together with the operating lever, to the other side of the center line of the machine, thus placing 70 the operating lever in position to engage in notch 19. After the boards are nailed to the side now uppermost, the assembled box is removed from the fixture and the fixture returned to its starting position by two 75 depressions of the treadle.

While I have shown a fixture suitable for a box with one center partition, it will readily be understood that fixtures may be 80 provided for the machine for any shape or size of box, with any number of partitions, up to the limit of the size of the stand and that such fixtures might be made interchangeable.

Having thus described my invention and 85 its operation, what I claim as new and wish to protect by Letters Patent is:

1. In a box making machine, of the class 90 described; a stand; a box assembling fixture resting on said stand; discs rigidly attached to pivots mounted on the ends of 95 said assembling fixture; a plurality of right hand and a plurality of left hand notches cut on each of said discs; vertical guides, in which said pivots slide, attached to the stand; a treadle mounted on the stand; levers attached to said treadle engaging in the notches cut in the said discs; and automatic means for changing the engagement 100 of these levers from the right hand notches to the left hand notches and vice versa, when the treadle is depressed.

2. In a box making machine, of the class 105 described; a stand; a box assembling fixture resting on said stand; means provided on said fixture for correctly locating certain members of a box; discs rigidly attached to pivots mounted on the ends of 110 said assembling fixture; a plurality of right hand and a plurality of left hand notches cut on each of said discs; vertical guides, in which said pivots slide, attached to the stand; a treadle mounted on the stand; levers attached to said treadle engaging in the notches cut in the said discs; and automatic means for changing the engagement 115 of these levers from the right hand notches to the left hand notches and vice versa, when the treadle is depressed.

3. In a box making machine, of the class 120 described; a stand; a box assembling fixture resting on said stand; means provided on said fixture for correctly locating certain members of a box; discs rigidly attached to pivots mounted on the ends of 125 said assembling fixture; a plurality of right hand and a plurality of left hand notches cut on each of said discs; vertical guides, in which said pivots slide, attached to the stand; a treadle mounted on the stand; 130

levers attached to said treadle engaging in notches cut in the said discs; automatic means for changing the engagement of these levers from the right hand notches to 5 the left hand notches and vice versa, when the treadle is depressed; and means for counterbalancing the weight of the said as-

sembling fixture and of the box placed therein.

In testimony whereof, I, WALTER V. ¹⁰ HART, have signed my name this 22 day of April 1924.

WALTER V. HART.
